UNITED STATES PATENT OFFICE

JAMES KANTOR, OF CHICAGO, ILLINOIS, ASSIGNOR TO THE LIQUID CARBONIC CORPORATION, OF CHICAGO, ILLINOIS

CROWNING MECHANISM

Application filed September 20, 1928. Serial No. 307,121.

My invention relates to improvements in crowning mechanisms, and it consists in the combinations, constructions, and arrangements herein described and claimed.

An object of my invention is to provide a crowning mechanism which has novel means for feeding crowns to the crowning unit at desired intervals.

A further object of my invention is to provide a device of the type described which has novel means for gripping the crowns after they have been received by the crowning unit, whereby the crowns may be held against displacement until moved into locking engagement with the bottle.

A further object of my invention is to provide a device of the type described which has means for automatically releasing the crowns at desired intervals and means for automatically holding the remaining crowns after one crown has been automatically disposed in the crowning unit.

A further object of my invention is to provide a device of the type described which has novel means for automatically removing crowns which pass from the hopper in the wrong position.

Other objects and advantages will appear in the following specification, and the novel features of the invention will be particularly pointed out in the appended claims.

My invention is illustrated in the accompanying drawings, forming part of this application, in which

Figure 1 is a front elevation of the crowning mechanism, portions thereof being broken away,

Figure 2 is a sectional view of the crowning mechanism, portions thereof being shown in elevation,

Figures 3 and 4 are enlarged views of the crowning unit and the feeding unit in their different positions with respect to each other,

Figure 5 is a section substantially along the line 5—5 of Figure 3,

Figure 6 is a section substantially along the line 6—6 of Figure 4, and

Figure 7 is an enlarged sectional view of the crowning unit.

In carrying out my invention, I provide

a vertically extending stationary supporting member 1 which is hollow and which is provided with aligned elongated openings 2 in the walls thereof. A movable collar 3 is slidably disposed upon the support 1 and is provided with inwardly extending projections 4 which extend through the openings 2 and into the supporting member 1. A connecting rod 5 has one end disposed between the projections 4 and is pivotally secured thereto by a wrist pin 6 which extends through the connecting rod and into the projections 4 of the collar 3. The other end of the connecting rod 5 is operatively connected to a crank shaft 7, which may be actuated by any suitable power means, not shown.

A crowning unit 8 is rigidly secured to the collar 3 and is provided with a casing 9 having a hollow portion 10 which is threaded at one end as at 11 to receive a guide nut 12. A shoulder 13 is provided at the other end of the hollow portion 10 which is adjacent an opening 14.

A crowning plunger 15 is provided with an enlarged portion 16 movably disposed in the opening 14 and with an annular flange 17 arranged to normally rest upon the shoulder 13. A compression spring 18 is disposed between the flange 17 and the screw 11 for normally holding the plunger 15 downwardly.

A throat supporting collar 19 is secured to the casing 9 by means of a retaining member 20. A plurality of throat segments 21 is disposed in a circular arrangement and is pivotally secured at 22 to the collar 19. The segments 21 are provided with gripping portions 23 which are disposed adjacent the plunger 15, and with arcuate-shaped cam portions 24, which are disposed adjacent the enlarged portion 16.

Crown holders 25 are pivotally mounted at 26 upon the casing 9 of the crowning unit 8 and have their free ends normally held together by means of a tension spring 27. The free ends of the crown holders 25 extend beneath the crowning unit 8, as shown in Figure 1, and are provided with semicircular recesses 28 which provide a circular opening 29 when the members are together. Semicircular crown-retaining grooves 30 are pro-

vided in the free ends of the crown holders 25 adjacent the recesses 28. Crown chute receiving slots 31 are provided in the free ends of the crown holders 25. Transversely extending cam surfaces 32 are provided at the 5 outer extremities of the slots 31.

A head portion 33 is mounted upon the stationary supporting member 1, as shown in Figure 2. A crown hopper 34 is carried by the head portion 33 for receiving a plurality of crowns indicated at 35 in Figures 3 and 4. A positioning plate 36 is disposed in the hopper 34 and is provided with an annular groove 37 arranged to receive the crowns 35 in the desired position for directing the crowns from the hopper 34 through an outlet 38 and into a crown chute 39. An agitator 40 is disposed in the hopper 34 adjacent the plate 36 and is mounted upon a shaft 41. The shaft 41 is provided with a toothed portion 42, the teeth of which are in mesh with a rack 43. The rack 43 has its lower end operatively connected to the collar 3 and is arranged to be moved thereby.

The crown chute 39 is pivotally mounted upon the support 1 at 44. The lower end of the chute 39 curves inwardly at 45 and is provided with tapered cam surfaces 46. A handle 47 connected to the chute 39 through the medium of a spring 48 is provided for manually manipulating the chute if for any reason it becomes stuck in its movement. The crown chute 39 is provided with a discharging opening 49 which is positioned between the two extremities of the crown chute and which communicates with the passageway 50 in the chute. A tapered surface 51 is provided at the opening 49 for a purpose hereinafter described. Spaced-apart guide strips 52 are secured to the crown chute to form the passageway 50.

A crown-retaining latch 53 is pivotally mounted at 54 upon the lower end of the crown chute and has a finger 55 which extends inwardly for normally holding the crowns from passing from the chute. A trip pin 56 is carried by the lower end of the chute 39 a short distance from the crown-retaining latch 53. A trip lever 57 is pivotally mounted upon one of the crown holders 25 and is normally held in a horizontal position by means of a helical spring 58. The trip lever is provided with a contacting shoulder 59 positioned substantially at its center and a cam surface 60 disposed at its outer end.

A cam roller 61 is rotatably carried by the collar 3. A cam plate 62 is carried by the crown chute 39 and is in engagement with the cam roller 61. The upper edge of the cam plate 62 is tapered as at 63 for a purpose hereinafter described.

From the foregoing description of the various parts of the device, the operation thereof 65 may be readily understood. A bottle-sup-

porting table 64 is provided for moving bottles 65 intermittently beneath and away from the crowning unit 8. When the crank shaft 7 is rotated and the device is set in motion, a reciprocatory movement is imparted to the 70 collar 3 and its cooperating parts. Let us assume that the collar 3 and its cooperating parts are in their uppermost position, as shown in Figure 3. When the collar 3 is moved downwardly, the crown will have been 75 placed in the crown holder, as shown in Figure 2, and, as the crowning unit 8 is moved toward one of the bottles 65, the plunger 15 will hold the crown in engagement with the top of the bottle while the top of the bottle 80 passes between the segments 21. As the crown and the top of the bottle pass between the segments 21, the corrugated edge of the crown is bent inwardly around the bead of the bottle, and thus firmly secured in place. 85

As the collar 3 and its cooperating parts move upwardly, the spring 18 holds the plunger 15 in engagement with the crown upon the bottle until the crowning unit has been removed from the top of the bottle. The 90 unit continues in this movement upwardly, and in this movement the cam roller 61 rides upon the cam plate 62 until it reaches the upper extremity of the cam plate. At this position the crown chute 39 is allowed to 95 swing inwardly about its pivot, as shown in Figure 4—thus moving the free end of the crown chute into engagement with the crown holders 25.

As the lower end of the crown chute 39 100 swings inwardly, the cam surfaces 46 contact with the surfaces 32 of the crown holders 25 and force the crown holders away from each other a slight distance. During this movement the crown-retaining latch 53 engages with the shoulder 59 of the trip lever 57—thus swinging the finger portion 55 free from the adjacent crown and allowing the crown to be passed inwardly and be received in the crown-retaining grooves 30. 105

When the lower end of the crown chute reaches its innermost position, the cam surface 60 of the trip lever 57 will have engaged with the trip pin 56 and will have been moved upwardly into the position shown in Figure 115 4. In this position the crown-retaining latch will be released and returned to its normal position by means of the spring carried thereby—thus holding the remaining crowns in the crown chute. When the crown chute is moved away from the crowning holders 25, the spring 27 will draw the crown holders together—thus frictionally holding the crown against displacement until the crowning unit is again moved toward one of the bottles 65. 120 125

As the collar 3 is moved, the agitator 40 is oscillated, thus disturbing the crowns in the crown hopper 34 so that they will fall into the groove 37 and pass through the outlet 38 and into the passageway 50 of the crown 130

chute 39. As the crowns pass into the passageway 50, they will be held by the crown-retaining latch 35 and allowed to move downwardly as the crowns are removed therefrom.

- 5 If any of the crowns should enter the passageway 50 in the wrong position, the projections upon the crowns will catch upon the tapered surface 51 and be thrown from the crown chute through the outlet 49. The handle 47
10 upon the crown chute provides a means for manually holding the crown chute from dispensing the crowns in the crown holders when desired.

It will therefore be observed that as the 15 collar 3 is moved upwardly, the agitator 40 is actuated, causing the crowns to pass from the hopper into the crown chute, and, as the collar 3 reaches its uppermost position, the crown chute is allowed to swing inwardly, due 20 to the fact that the cam roller 61 passes above the upper edge of the plate 62 and allows the plate to pass beneath the cam roller. During this swinging in of the crown chute, the crown holders 25 are forced apart, a crown 25 is deposited in the crown-receiving grooves 30, and is held in place by the spring 27, when the chute is again swung outwardly. The crowns in the chute will be held by the crown-retaining latch 53 as the collar 3 is 30 moved downwardly, bringing the crowning unit into operative engagement with one of the bottles 65 so as to cause the throat segments 21 to crimp the crown around the bead of the bottle. The collar 3 is then moved 35 upwardly so as to allow the crowned bottle to pass from beneath and another one of the bottles 65 to pass beneath the unit.

I claim:

1. A crowning mechanism comprising supporting means, means mounted for reciprocatory action upon said supporting means and being provided with a crown holder, a crown supply hopper carried by the supporting means and having an outlet opening, and 45 a crown chute movably carried by the supporting means and arranged for placing the outlet opening in said hopper in communication with the crown holder, said crown holder comprising a pair of elements movable relatively with respect to each other and actuated by engagement with the crown chute for receiving a crown and positively gripping the same.

2. A crown mechanism comprising supporting means, means mounted for reciprocatory action upon said supporting means and being provided with a crown holder, a crown supply hopper carried by the supporting means and having an outlet opening, a crown 55 chute movably carried by the supporting means and arranged for placing the outlet opening in said hopper in communication with the crown holder at predetermined intervals, and means associated with the means 60 mounted for reciprocatory action for moving

the crown chute toward and away from the crown holder at predetermined intervals, said crown holder comprising a pair of jaws movable relatively with respect to each other and arranged to be spread when engaged by a portion of the crown chute for receiving a crown, said jaws being further arranged to move toward each other for positively gripping the crown when the crown chute is moved away from the same.

3. A crowning mechanism comprising supporting means, means mounted for reciprocatory action upon said supporting means and provided with a crown holder comprising a plurality of laterally separable elements biased towards crown supporting position, a crown supply holder carried by the supporting means and having an outlet opening, a crown chute movably carried by the supporting means and arranged for placing the outlet opening in said supply holder in communication with the crown holder and restraining means for the crowns in said chute operated by the initial movement of the chute to placing position to release the first crown and by a continued movement of the chute to restrain the successive crowns.

4. A crowning mechanism comprising supporting means, means mounted for reciprocatory action upon said supporting means and being provided with a crown holder comprising a plurality of laterally separable elements biased towards crown gripping position, a crown chute movably carried by the supporting means and arranged for placing the outlet opening in said hopper in communication with the crown holder and having means adapted by the movement of said chute into communicating position to engage and separate said elements to receive a crown.

5. A crowning mechanism comprising supporting means, means mounted for reciprocatory action upon said supporting means and being provided with a crown holder comprising a plurality of holding elements separable in a horizontal plane and biased toward crown holding position, a crown supply hopper carried by the supporting means and having an outlet opening, a crown chute movably carried by the supporting means and arranged for placing the outlet opening in said hopper in communication with the crown holder and restraining means for the crowns in said chute operated by the initial movement of the chute to placing position to release the first crown and by a continued movement of the chute to restrain the succeeding crowns.

6. In a device of the character described, the combination with a crowning unit, of a crown holder associated with said unit for holding a crown while the same is moved into engagement with a bottle, a crown chute associated with said unit for delivering crowns to said holder and movable into and out of plac-

ing position, the crowns being fed through said chute by gravity and restraining means for the crowns in said chute operated by the initial movement of the chute to placing position to release the first crown and by a continued movement of the chute to restrain the succeeding crowns.

7. In a device of the character described, the combination with a crowning unit, of a crown holder associated with said unit for holding a crown while it is moved into engagement with a bottle, a crown chute movably associated with said holder for delivering a crown thereto, a restraining member for holding the crowns in said chute against movement by gravity and means for engaging and moving said restraining member out of holding position during the initial placing movement of the chute and disengaged from said restraining means to permit the same to return to normal position by a continued movement of the chute into placing position.

8. In a device of the character described, the combination with a crowning unit, of a crown holder for holding a crown while it is moved into engagement with a bottle, a crown chute for supplying crowns to said holder and movable to and from said holder, a restraining member normally in restraining position to prevent the movement of the crowns through said chute by gravity, a relatively stationarily mounted trip member adapted to engage said restraining means and move the same out of the path of the crown during the initial movement of the chute toward the holder and means operated by a continued movement of the chute for disengaging said trip member to permit the restraining means to move back to restraining position.

40 Signed at Chicago, in the county of Cook and State of Illinois this 10th day of Sept. A. D. 1928.

JAMES KANTOR.
